FIG. 5

FIG. 6

INVENTOR.

Park L. Newbold

UNITED STATES PATENT OFFICE

2,541,536

AUTOMATIC DRAIN SPOUT

Park L. Newbold, Cedar Rapids, Iowa

Application July 11, 1946, Serial No. 682,878

2 Claims. (Cl. 137—9)

1

This invention relates to a drain spout that carries the rain water away from the building while it is raining and automatically returns to a position alongside the wall upon cessation of the rain.

It is the object of my invention to provide a device of simple and inexpensive construction that will eliminate the necessity of having a drain spout extending across walks, driveways and other frequented places during the time it is not raining.

Another object of my invention is to provide a device that reduces the hazards of tripping over permanent drain pipes extending across walks, by replacing them with an automatic pipe that is in this position only when it is raining.

Another object of my invention is to provide a device that requires little attention and is inexpensive to install.

Other and further features and objects of the invention will be more apparent to those skilled in the art upon a consideration of the accompanying drawings and following explanation, wherein is disclosed a single exemplary embodiment of the invention, with the understanding, however, that such changes may be made therein as fall within the scope of the appended claims without departing from the spirit of the invention.

Figure 1 is a view of my device in normal position with the discharge pipes alongside the wall.

Figure 2 is a view of my device in discharging position and showing the return balance weight and secondary discharge pipe control valve.

Figure 3 is an enlarged view of a part of the lower hinged bracket and showing in particular the turning track, pulleys, control valve levers and tank pivot support.

Figure 4 is a view of levers that operate the valve regulating the flow of water from the secondary discharge pipe.

Figure 5 is a side view of the frame and tank and illustrates in particular the upper and lower hinged brackets and balance weight.

Figure 6 is a front view of the lower part of the tank, turning track and lower hinged bracket.

The views of the device show the discharge pipes as turning from left to the right, however, it is understood that a reversal of the turning mechanism will produce a turning movement opposite of that shown.

Referring now to the drawings, a preferred embodiment of my invention includes a tank indicated generally at 10, a main discharge pipe 11, a secondary discharge pipe 12, a main frame 13,

2

hinged U shaped brackets 14, a turning track 15, a return weight 16, a control valve 17, valve control levers 18 and an inlet pipe 19.

The U shaped hinged members 14 are pivotally connected to supports 20 at 56. Said supports are attached to main frame 13 at 21. A pivot arm 22 is attached to the top rim of the tank 10 and extends inward to the center of said tank and is pivotally connected to the upper U hinged member 14 at 23. A tank pivot support 24 is secured to the bottom of the tank 10 and is pivotally connected to the lower U hinged bracket at 25. A member 26 and tension spring 27 connect the upper and lower U hinged brackets 14, between which, the tank 10 is pivoted. The return weight 16 is pivotally connected to a lever arm 28 at 33. Lever arm 28 is pivotally connected to anchor member 30 at 29. A connecting member 31 is pivotally connected to lever arm 28 and lower hinged U bracket 14 at 32.

The connecting member 26 and tension spring 27 are pivotally connected to hinged U brackets at 34. A lid 35 is supported by an L-shaped member 36 and is held in place by wing nut 37. Member 36 is secured to the inlet pipe 19 and serves as a support for the lid 35.

A member 38 connects with the valve 17 at 57 and extends to the main control lever 18, a tension spring 39 is attached to member 38 and anchored to 12. An upright support 40 is secured to 12 and an adjustable arm 41 is attached to band 43 and held in place by set screw 42.

The angled base of the main frame member 13 is strengthened by a brace 44. A stop member 45 is attached to the outward end of the angled base.

A pair of pulleys 46 are attached to member 47 so as to revolve, member 47 is attached to the tank base at 48. A track 15 bent to the form of an exaggerated semi-circular spiral is attached to the main frame 13 at 49 and at its lower part at 50. An extension member 51 is attached to the lower U hinged bracket for additional leverage. A pipe member 52 is provided for the flow of water from the tank 10 into the secondary discharge pipe 12, and a return stop member 53 is secured to the lower U bracket to arrest the movement of the secondary discharge pipe 12 upon its returning to normal position. A member 54 is attached to the lower U hinged bracket adjacent to stop member 53 and its function is to contact trip valve control lever 18 upon the return of the secondary discharge pipe 12 to normal position. One end of a tension spring 55 is secured to left trip valve control lever 18 while

the other end is anchored to tank pivot support 24. The right control valve lever 18 is connected with member 38 at 57 and upon contact with stop member 45 a latching action is effected with the left trip member 18, thereby holding the valve 17 open. These two control members 18 are so constructed that their ends latch and unlatch at a predetermined position of the discharge pipe 12. Member 58 is anchored to member 12 and acts as a base for the valve control levers 18.

In use the device is attached to the foundation or side of a building as shown in Figure 1 and this is considered normal position. As it commences to rain, the water enters the tank 10 through inlet pipe 19. As soon as the proper weight of water enters the tank, pressure is applied to the upper pulley 46 which is then making contact with the top portion of the spiral-like track 15. The pulley then rolls downward on the track causing a turning movement of the tank 10, discharge pipes 11-12 and other parts of the mechanism. At the time this turning movement is taking place the U shaped hinged brackets 14 are moving downward and the weight 16 moves upward. As soon as the turning movement nears 90 degrees the right valve control lever 18 contacts stop member 45 and causes valve 17 to open, left trip control lever 18 moves into place against right lever 18 and remains in this position thereby holding valve 17 open. We are assuming the height of the water in the tank 10 has now reached the main discharge pipe 11 and is flowing from the tank and also a small amount from the bottom of the tank 10 through the outlet 52 into the secondary pipe 12 and discharged through the valve 17. This flow of water will continue in this manner until the amount of water entering the tank is less than the amount being discharged through the secondary discharge pipe 12. When this occurs the water will stop flowing from the main pipe 11 and continue only through 12 until the weight of water remaining in the tank is less than the pull being exerted by the weight 16 on the lower U bracket 14. When this point of balance has been reached the weight 16 moves downward and through lever action forces lower pulley 46 against the under side of the track 15 and causes the tank and discharge assembly members to turn and move back to normal position. As the discharge pipes 50

near the 90 degree return distance the control lever stop member 54 contacts the left trip control lever 18 and causes it to break contact with right lever 18 thereby permitting the water control valve 17 to return to closed position.

The device now is assumed to be back to its normal position with the secondary pipe 12 resting against member 53 and left trip control lever 18 contacting 54 and maintaining light pull on spring 55.

Tension of spring 39 keeps valve 17 closed until opened by contact of right control lever 18 with member 45. The action of the device is automatic and is accomplished by applying the weight of water entering and discharging, to a combination of members coordinated as a unit.

I claim as my invention:

1. In a drain spout the combination of a main frame, a pair of U shaped bracket members pivotally attached to same, a tank, a cover means for same, an inlet, main and secondary discharge pipes extending laterally from openings within said tank, means for pivotally suspending the tank perpendicularly between the U shaped brackets, a track bent to the form of an exaggerated semi-circular spiral and placed adjacent to the tank, roller means for connecting these two members, a balance tank returning means, an outlet valve attached to the secondary discharge pipe and means for controlling same substantially as the device described.

2. In a drain spout the combination of a main frame, an upper and a lower U shaped bracket pivotally attached thereto, a tank pivotally suspended perpendicularly between said U shaped brackets and adapted to move vertically in unison with same, a semi-circular spiral track anchored to the frame and roller connected to the tank in a manner that up and down movement of the U shaped brackets produces a revolving action of the tank, an inlet to the said tank, a cover means, a main and a secondary discharge pipe extending laterally from openings within the tank, an outlet valve attached to the secondary pipe, means for controlling same and a balance mechanism for reversing revolving movement of the tank substantially as the device described.
